BY Victor J. Evans ATTORNEY

UNITED STATES PATENT OFFICE.

WILLSE M. LAWRENCE, OF SPRINGFIELD, MASSACHUSETTS.

SPARK-PLUG WRENCH.

1,410,816.

Specification of Letters Patent. Patented Mar. 28, 1922.

Application filed July 28, 1920, Serial No. 399,532. Renewed August 29, 1921. Serial No. 496,753.

To all whom it may concern:

Be it known that I, WILLSE M. LAWRENCE, a citizen of the United States, residing at Springfield, in the county of Hampden and State of Massachusetts, have invented new and useful Improvements in Spark-Plug Wrenches, of which the following is a specification.

My present invention has for its object 10 the provision of a simple, inexpensive, readily adjustable spark plug wrench, possessed of a wide range of utility.

To the attainment of the foregoing, the invention consists in the improvement as 15 hereinafter described and definitely claimed.

In the accompanying drawings:

Figure 1 is a side elevation of a wrench constituting the preferred embodiment of my invention.

20 Figure 2 is a plan view of the same.

Figure 3 is a transverse section taken in the plane indicated on the line 3—3 of Figure 1.

Figure 4 is a side elevation of a modification as hereinafter explicitly referred to.

Referring particularly to Figures 1 to 3:

1 is the handle member of my novel wrench. The said handle member is provided at its forward end with an angularly 30 disposed jaw 2, the inner side of which is of angular form in cross section as indicated by 3. At said inner end the handle member 1 is provided with a socket 4 in coincidence with the inner side of the jaw 2, and back 35 of said socket 4 the handle member is equipped, by preference, with a hammer-head 5.

At a point adjacent to the jaw 2 the handle member 1 is provided with a pair of lugs 6, 40 and at an intermediate point of its length said handle member carries another pair of lugs 7.

Bearing in a threaded aperture 8 in the handle member, and in the same transverse 45 plane as the lugs 7 is a screw 9 the head of which is of wing-nut type, as shown, or of any other appropriate character.

Pivoted at 10 between the pair of lugs 6 is the adjustable jaw 11 of the wrench, which 50 adjustable jaw is of angular form in cross section at its inner side, as indicated at 12, and is of the proportional length illustrated so that when it is in its innermost position its free end will be substantially flush with 55 the free end of the fixed jaw 2. On the said jaw 11 is an arm 13 that is disposed and mov-

able between the lugs 7 and is subject to the action of the adjustable screw 9 so that through the medium of the said screw the jaw 11 may be strongly set against a spark 60 plug so that there will be no liability of a casual release of the wrench from the spark plug.

It will be apparent from the foregoing that my novel wrench is capable of being 65 adapted to spark plugs of various sizes with the greatest facility, and this, notwithstanding the fact that the wrench is extremely simple and inexpensive in construction and is free of delicate parts such as are likely to 70 get out of order after a short period of use.

It will also be apparent that incident to the application of my novel wrench to a spark plug, the upper portion of the plug will be received and accommodated in the 75 socket 4.

In the modification shown in Figure 4, the lugs 7 of Figures 1 to 3 are dispensed with, and a single pair of lugs 6^a is employed, the said lugs 6^a being comparatively elongated 80 as illustrated and being therefore adapted to resist any tendency of the arm of the adjustable jaw to swing laterally under great stress or strain. It will be also observed by reference to Figure 4 that the handle member 1 is provided with a curvilinear tail portion 15 which is adapted to add to the range of usefulness of the wrench because of its adaptability to be interposed between a wheel rim and a tire casing with a view to 90 prying the casing from the rim.

Manifestly the modification is possessed of all the features of advantage ascribed to the form shown in Figures 1 to 3.

Having thus described the invention, I 95 claim:

1. A wrench comprising a handle member having a threaded aperture at an intermediate point of its length and also having an angularly disposed jaw at one end, a socket 100 in coincidence with the inner side of said jaw, and a pair of lugs adjacent to the inner end of said socket; a screw bearing in the said threaded aperture of the handle member, and an adjustable jaw pivoted between 105 the said lugs and having a rearwardly extending arm the rear portion of which is opposed to the inner end of the screw.

2. A wrench comprising a handle member having a threaded aperture at an intermediate point of its length and also having an angularly disposed jaw at one end, a socket 110

- in coincidence with the inner side of said jaw, and a pair of lugs adjacent to the inner end of said socket, a screw bearing in the said threaded aperture of the handle member, and an adjustable jaw pivoted between the said lugs and having a rearwardly extending arm the rear portion of which is opposed to the inner end of the screw; the inner side of the fixed jaw being of angular 5 form in cross section and the inner side of the adjustable jaw being of angular form in cross section and being of a relative length whereby in its innermost position the free end of the adjustable jaw will be substantially flush with the free end of the fixed jaw.
- 10 3. A wrench comprising a handle member with pairs of lugs at its inner side and a threaded aperture in the same transverse plane as one pair of lugs, and an angularly disposed jaw at its forward end the inner side of which is of angular form in cross sec-
- 15
- 20

tion and a socket adjacent to said forward end in coincidence with the inner side of the fixed jaw, in combination with a screw bearing in the threaded aperture of the handle member, and an adjustable jaw having an angular inner side and also having an arm movable between the lugs of the pair remote from the fixed jaw and subject to the action of the screw.

4. The combination in a wrench, of a handle member having an angularly disposed jaw at one end and also having a socket back of and in coincidence with the inner side of said jaw, an adjustable jaw opposed and arranged in spaced relation to the first-named jaw, said adjustable jaw being movably connected with the handle member, and means cooperating with the handle member and the adjustable jaw to adjust the latter.

30 In testimony whereof I affix my signature.

35 WILLSE M. LAWRENCE.
